UNITED STATES PATENT OFFICE.

HARRY J. HOOK, OF CHESTER, PENNSYLVANIA, ASSIGNOR TO CROMPTON & KNOWLES LOOM WORKS, OF WORCESTER, MASSACHUSETTS, A CORPORATION OF MASSACHUSETTS.

THREAD CUTTER FOR WEFT-REPLENISHING LOOMS.

Application filed December 14, 1926. Serial No. 154,808.

This invention relates to improvements in thread cutters for weft replenishing looms more particularly, though not necessarily, of the multi-color type, and it is the principal object of the invention to provide a cutter so controlled as to operate prior to transfer.

In weft replenishing mechanisms there is usually provided a transferrer arm which acts on the transferring beat of the loom to insert a fresh bobbin in the depleted shuttle. It is desirable to cut the filling extending from the selvage to the exhausted bobbin prior to the time of transfer so that the trailing end may be drawn out of the shuttle box. It is an important object of my present invention to accomplish this result by employing a connection between the transferrer arm and the cutting mechanism whereby the cutter is held against cutting action so long as the transferrer arm is raised but is released to cut during the first part of the downward motion of the transferrer arm and before transfer is completed.

It is a further object of my present invention to provide a cutter wherein the energy necessary to open the same is stored in a resilient device prior to the time of transfer and released by the transferrer arm at the first part of the downward stroke of the latter, the transferrer arm acting as a trigger to release the cutter.

It is a more particular object of my invention to provide controlling mechanism for the cutter whereby the time at which the cutter is released to sever the thread may be varied with respect to the vertical position of the transferrer arm so that cutting may be accomplished either at the start of the transferring stroke or a short time thereafter, depending upon the result desired.

A still further object of my invention is to provide a cutter on a shuttle placer and arrange for releasing the cutter and operating the placer by the transferrer arm.

With these and other objects which will appear as the description proceeds, my invention relates to the arrangements and combinations of parts hereinafter set forth, and more particularly pointed out in the claims.

In the accompanying drawings, wherein a convenient embodiment of my invention is set forth.

Fig. 1 is a side elevation of the multi-color

replenishing mechanism viewed from the interior of the loom, and having my invention applied thereto in normal position.

Fig. 2 is a view similar to Fig. 1 but showing the cutter moved to cutting position but held against operation by the transferrer arm,

Fig. 3 is a view similar to Fig. 2 but with the transferrer arm moving downwardly and the cutter moved to cutting position,

Fig. 4 is an enlarged horizontal section 65 through the cutter and clamp on line 4—4 of Fig. 1,

Fig. 5 is an enlarged vertical section 70 through the cutter and clamp on line 5—5 of Fig. 1,

Fig. 6 is an enlarged detail horizontal section 75 on line 6—6 of Fig. 1,

Fig. 7 is a fragmental vertical section on line 7—7 of Fig. 1, and

Fig. 8 is an enlarged view of the pivoted 75 controlling device which cooperates with the transferrer arm and the cutter.

Referring to the drawings, it will be seen that I have provided a loom frame 10 on which is mounted a weft replenishing mechanism 11 of the multi-color type. A top shaft 12 oscillates in bearing 13 prior to indication for transfer and has secured thereto an arm 14 connected to a link 15 operatively connected to a second link 16. Said links are 80 connected yieldingly by a compression spring 85 17 and rod 18, the upper end of the latter being secured to the bottom of link 15. A compression spring bears against the upper 90 part of the second link 16 so that upward movement of link 15 tends to raise link 16, although the latter may remain at rest if an obstruction lies in the path of any part operatively connected thereto.

The lower end of link 16 is pivoted to a 95 lever 19 which in turn is pivoted at 20 on a forked mounting 21 having a stud 22 which extends through hub 23 of a stand 24 bolted to the frame 11.

The lower leg 25 of the lever 19 is slotted 100 at 26 to receive a roll 27 mounted on transferrer arm 28. The roll and slot may or may not be used, but when used, said slot will be in the form shown in Fig. 7 to cooperate with the roll to move the lever 19 toward 105 the shuttle on transferring beats when the transferrer arm is moving downwardly, the movement toward the shuttle occurring at

the beginning of the downward movement of the transerrer arm. The latter is pivoted as at 29 to the frame 11 and may be actuated in any approved manner as by a bunter 5 on lay L indicated at 30 in dotted lines.

The bottom of leg 25 has bolted thereto a thread cutting and clamp unit 31 shown more particularly in Figs. 4 and 5. A stud 32 secured to the member 31 has pivoted thereon 10 a cutter blade 33 the forward end of which is off-set as at 34 and extends in a notch 35 of an arm 36 also pivoted on the stud 32. Said arm is provided with a pin 37 to which is pivoted the lower end of a rod head 38. 15 A torsion actuating spring 39 has one end thereof anchored in the arm 36 and the other end held by a nut 40 threaded on the stud 32 and held in place by a check nut 41. The normal tendency of the actuating spring 39 20 is to hold the cutter jaw closed in the position shown in Figs. 1 and 5. The relatively stationary cutter blade 42 is held to the unit 31 partly by a shoulder 43 of the stud 32 and partly by a screw 44. A screw 45 secured 25 into the unit 31 acts to limit upward movement of the movable cutter blade 33 and forms one support for a clamp member 46, the other support being the stud 32. The cutter blade 33 lies between said stationary 30 cutter blade 42 and clamp 46, the latter, if desired, being made of fibre.

In the operation of the mechanism thus far described lever 19 will be given a slight right hand oscillation prior to transfer to 35 move to the position shown in Fig. 2. The matter already described may be the same as set forth in patent to Ryon No. 1,030,748, and McGuiness, No. 1,261,417 and for further description of the operation of the devices heretofore described reference may be 40 had to said patents.

My present improvement relates more particularly to the means for controlling the cutter and the time of the operation thereof, 45 and in carrying out my invention I provide a lever 50 pivoted at 51 to the frame 11 and having a substantially horizontal arm 52 attached to the upper end of a rod 53 the lower end of which is secured to the rod head 38. Said lever 50 has a substantially vertical arm 54 provided with a groove 55 in which is located an adjustable releasing plate 56 held in position by a screw 57. Said screw passes through a slot 58 in the plate and is secured 50 in the vertical arm 54. The lower end of plate 56 is provided with a downwardly opening slot 59 which is normally occupied by pin 60 secured to the transerrer arm and moving therewith. As a matter of convenience the plate 56 and arm 54 are located between the roll 27 and the transerrer arm 28 55 when the roll is used.

In the operation of my improvement when the link 15 is raised lever 19 will rock around stud 20 to move the thread cutting and

clamping unit 31 to the position shown in Fig. 2. During this movement the transerrer arm is in its raised position and pin 60 is therefore located in the slot 59. For this reason the upper end of rod 53 is held 70 against downward movement and because of the centers of the lever 19, stud 32, pin 37 and the upper end of said rod 53, the movable cutter 75 33 will move relatively to the fixed blade 42 so as to open, as indicated in Fig. 2. Inasmuch as the rod 53 can not move downwardly torsion spring 39 will be given a slight twist as the cutters move to open position, this twist tending to close the cutters.

When the transerrer arm starts down pin 80 60 will move out of the notch 59 and spring 39 will be free to raise the cutter blade 33 so as to cut the filling. In this way assurance is given that the cutter will operate at the beginning of the downward stroke of the 85 transerrer arm before the fresh bobbin has started to enter the depleted shuttle.

The closing of the cutter is accomplished by a movement of the lever 50 to the position shown in Fig. 3, where it will be noted that the slot or notch 59 is out of registry with the pin 60. As the transerrer moves downwardly the lay will move forwardly and the back 61 of the box will engage the unit 31 to move the same forward to the position 95 shown in Fig. 1. This last operation is completed while the transerrer arm is down so that the lever 50 and therefore notch 59 will be returned to normal position while the pin 60 is in its lowest position. As the lay 100 recedes and the transerrer arm rises the pin 60 will enter the slot 59 and the parts will be restored to position shown in Fig. 1.

As previously stated it is not necessary to employ the roll 27 and cam slot 26, the unit 105 31 moving to rear position independently of the placing action and before the latter occurs. When the cam slot is used, however, it is desirable to delay the cutting until the cutter and clamp have moved, inasmuch as the 110 motion is away from the selvage and if the cutting took place before the cutter stopped moving toward the shuttle, the thread might pull out of the clamp. It is to permit the delay of the cutting and clamping until after 115 the shuttle has been placed that I have provided the adjustable plate 56, the slot 58 enabling the plate to be moved down so that pin 60 can remain in contact with the plate and therefore prevent cutting until after the 120 shuttle is placed. Of course where the roll and placer are omitted the cutting may take place earlier in the downward movement of the transerrer arm.

From the foregoing it will be seen that I 125 have provided a cutter and clamp wherein energy is stored in a resilient device at some time prior to the beginning of the transferring stroke and that immediately following the beginning of the transferring operation 130

and before this operation is completed the resilient device will be released. It will further be seen that the time for releasing the spring 39 can be varied by adjusting the vertical position of the plate 56 and that the rod head 38 affords means for adjusting the angular position of lever 50 so that the pin 60 can be made to enter the slot 59. It will further be seen that the cutter is mounted on the shuttle placer which derives its movement from the transferrer, and that the cutter is also released by the transferrer. Furthermore, when the shuttle placer feature is used the releasing of the cutter can be delayed until after the unit 31 has stopped moving from the selvage of the cloth.

Having thus described my invention, it will be apparent that changes and modifications may be made therein by those skilled in the art without departing from the spirit and scope of the invention, and I do not wish to be limited to the details herein disclosed but what I claim is:

1. In a weft replenishing loom, transferrer mechanism, a thread cutter, actuating means tending normally to close the cutter, locking means holding the cutter open against the action of the actuating means when said cutter is in cutting position, and inter-connections between the transferrer mechanism and the locking means to release the actuating means during the first part of the operation of the transferrer mechanism on a transferring beat of the loom, whereby the actuating means will operate the cutter prior to the completion of the transferring movement of the transferrer mechanism.

2. In a weft replenishing loom, a transferrer arm, a thread cutting and clamping unit normally in non-cutting position, means acting prior to transfer to move the unit to cutting position, inter-connections between the cutter and the transferrer arm to open said cutter as the same moves to cutting position when the transferrer arm is in raised position, and means controlled by the transferrer arm and effective during the first part of the downward movement thereof to close the cutter.

3. In a weft replenishing loom, a transferrer arm, a thread cutting and clamping unit normally in non-cutting position, the cutter and clamp being normally closed when in non-cutting position, means to move the unit toward cutting position prior to transfer means to open the cutter and clamp as the unit moves toward cutting position, a resilient member tending normally to close the cutter and clamp, and devices operatively connected to and controlled by the transferrer arm holding said resilient device against action while the transferrer is at rest and releasing said resilient device during the downward stroke of the transferrer arm, whereby said resilient device will close the cutter and clamp.

4. In a weft replenishing loom, a transferrer arm, a thread cutting and clamping unit normally in non-cutting position with the cutter and clamp closed, a resilient device connected with the cutter and clamp and tending normally to move the same to closed position, means operative prior to transfer to move the unit to cutting position, means effective as the unit moves toward cutting position to open the cutter and clamp against the action of the resilient device, mechanism operatively connecting the resilient device and the transferrer arm and tending to hold the resilient device inactive while the transferrer arm is at rest, said transferrer arm at the beginning of its downward stroke becoming disconnected from the mechanism, whereby the latter is released and the resilient device is effective to close the cutter and clamp.

5. In a weft replenishing loom, a transferrer arm, a thread cutting and clamping unit normally in non-cutting position with the cutter and clamp closed, a resilient device tending normally to close the cutter and clamp, movable mechanism operatively connected to the resilient device and normally held against motion by engagement with the transferrer arm when the latter is at rest to hold the resilient device against action, and means to move the unit to cutting position and to open the cutter and clamp, said transferrer arm at the beginning of its downward stroke on a transferring beat of the loom becoming disengaged from the mechanism so that the latter is movable, whereby the resilient device will close the cutter and clamp before the completion of the transferring movement of the transferrer arm.

6. In a weft replenishing loom, a transferrer arm, a thread cutting and clamping unit normally in non-cutting position with the cutter and clamp closed, a resilient device operatively connected to the cutter and clamp and tending normally to move the same toward closed position, a lever movable about a fixed center and operatively connected to the resilient device, means defining a connection between the transferrer arm and the lever to prevent movement of the latter when the transferrer arm is at rest and in raised position, and means acting prior to transfer to move said unit to cutting position and to open the cutter and clamp, the transferrer arm moving out of controlling relation with respect to the lever during the first part of the transferring stroke, thereby releasing the resilient device so that the same is effective to close the cutter and clamp.

7. In a weft replenishing loom having a shuttle, a transferrer arm, a combined thread cutting and clamping unit, a shuttle placer on which the unit is mounted, a resilient device tending normally to hold the cutter

- and clamp closed, mechanism normally restrained against movement by contact with the transferrer arm when the latter is inoperative, means to move the cutter and clamp to cutting position with the cutter and clamp open prior to a transfer, operative connection between the transferrer arm and the shuttle placer to give the latter a shuttle placing movement during the first part of the downward movement of the transferrer arm, and means to maintain connection between the transferrer arm and said mechanism to restrain movement of the resilient device until after the placer has received its shuttle placing movement from the transferrer arm, said transferrer arm thereafter moving out of controlling position with respect to the mechanism whereby the resilient device is released to close the cutter and clamp after the shuttle has been placed. 8. In a weft replenishing loom, a transferrer arm, a combined cutter and clamp normally in non-cutting position with the cutter and clamp closed, means to move the combined cutter and clamp to cutting position prior to transfer and to open the cutter and clamp, a device operatively connected to the cutter and capable of having energy stored therein as the cutter is opened and tending to close the cutter after energy has been stored therein, and a connection from the transferrer arm effective during the first part of the movement of the transferrer arm on a transferring beat of the loom to release the stored energy in the device, whereby the latter will close the cutter and clamp. 9. In a weft replenishing loom, transferrer mechanism, a thread cutting and clamping unit normally in non-cutting position with the cutter and clamp closed, means to move the cutter and clamp to cutting position prior to the actuation of the transferrer mechanism with the cutter and clamp open, a device operatively connected to the cutter and clamp to have energy stored therein as the unit moves toward cutting position and tending to close the cutter after energy has been stored therein, and means operated by the transferrer mechanism during the first part of the transferring movement thereof to release the energy stored in the device, whereby the cutter and clamp will be given an operative movement prior to the completion of the transferring movement of said transferrer mechanism.

In testimony whereof I have hereunto affixed my signature.

HARRY J. HOOK.
